A. C. NORDMAN

DETACHABLE FUSEE AND TORPEDO HOLDER FOR RAILROAD LANTERNS

Filed May 7, 1923

Inventor:
Anna C. Nordman.
By *Frank J. Harrow*
Attorney.

UNITED STATES PATENT OFFICE.

ANNA C. NORDMAN, OF KIRKWOOD, MISSOURI.

DETACHABLE FUSEE AND TORPEDO HOLDER FOR RAILROAD LANTERNS.

Application filed May 7, 1923. Serial No. 637,102.

To all whom it may concern:

Be it known that I, ANNA C. NORDMAN, a citizen of the United States, residing at Kirkwood, in the county of St. Louis and 5 State of Missouri, have invented a certain new and useful Detachable Fusee and Torpedo Holder for Railroad Lanterns, of which the following is a specification.

My invention relates to a detachable fusee 10 and torpedo holder for railroad lanterns, and, it is a distinct and practical improvement to overcome certain practical objections to, and defects in, fusee holders which are permanently fixed to the railroad lantern. 15

The object of my invention is the provision of a fusee and torpedo holder which can be quickly attached to, or detached from a standard railroad flagmen's lantern by 20 merely slipping the device over the lantern frame without making any changes in the lantern construction.

A further object of the invention is the provision of a fusee holder so constructed as 25 to provide two opposed pairs of open ended tubular receptacles for the reception of four fusees used by railroad men for signaling purposes.

A still further object of the invention is 30 the provision of a device of the above character which will be simple and comparatively inexpensive in construction, light in weight, strong, durable and highly efficient for the purposes intended.

With the above and other objects in view, 35 as will appear hereinafter, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a side elevation of a standard railroad flagmen's lantern equipped with a fusee and torpedo holder embodying the features of my invention, said holder being shown in sectional elevation.

Fig. 2, is a top plan view of the lantern and fusee holder applied thereto.

Fig. 3, is a view taken on line 3—3 of Fig. 1.

Fig. 4, is a side elevation of my invention.

Fig. 5, is a view taken on line 5—5 of Fig. 4.

Fig. 6, is a view taken on line 6—6 of Fig. 4.

Referring to the drawings, the reference character A represents a standard railroad flagmen's lantern having the base ring 1. 2 indicates the lower looped ends of the lantern frame wires 3. 4 represents the ear formed integral with two of the lantern frame wires 3 to which are connected the usual lantern handle or bail 5.

In carrying out the aim of my present invention, I employ a suitable holder base ring 6 which is preferably made from a single piece of metallic flat strip stock.

A pair of fusee holder tubes 7 are suitably fixed, such as by soldering or otherwise, at their lower ends to opposite sides of the holder base ring 6. The tubes 7 of each pair are suitably spaced apart on their respective sides of the ring 6, as shown in Figs. 2, 3, 5 and 6. The lower ends of the tubes 7 are preferably flush with the lower edge of the holder base ring 6.

8, represents an upper holder ring, preferably formed from a single strand of wire. This ring is preferably less in diameter than the lower base ring 6 and it is suitably fixed to the tubes 7, such as by soldering, or otherwise. The ring 8 is fixed to the tubes 7 near 85 their upper ends, and, the tubes 7 are disposed to the outside of the upper ring 8 and also to the outside of the lower or base ring 6.

To further strengthen the support of the 90 fusee holder tubes 7 to prevent any possible chance of displacement thereof, I unite each pair of tubes upon each side of the holder rings with a short flat strip connection 9, which is suitably fixed to each pair of tubes, 95 such as by soldering or otherwise.

The fusee holder is provided with an intermediate ring 10 which is preferably of the same diameter as the holder base ring 6. The ring 10 is suitably fixed to the tubes 8 100 at a suitable point above the holder base ring 6, such as by soldering, or otherwise.

The holder base ring 6, the intermediate ring 10 and the tube connector strips 9 are each provided with an offset portion 11 to 105 increase the diameter thereof to permit the fusee holder to be slipped over the lantern in applying it to the lantern. This arrange-

ment permits the bail 5, as well as the ears 4 of the lantern to pass through the offset portions of the lower and intermediate rings and the tube connection strips, as this is the 5 widest point of the holder rings.

The fusee holder tubes are directed upward and slightly inward from the holder base ring 6, as the upper ring 8 is preferably of less diameter than rings 6 and 10. This 10 construction causes the top ring 8 to act as a stop ring to engage the upper face of the ears 4 to prevent the fusee holder from being forced completely over the lantern from any cause, such as swinging the lantern in 15 signalling or otherwise.

The fusee holder tubes are each open at both ends and the wall of each tube is provided near its lower end with a plurality of inwardly directed indentations or protuberances to form stops within the tubes to prevent the fusee 12 carried in each tube from falling completely through the tube. By this arrangement, should any cinders, dirt or the like get into the tubes, it will fall 25 through the same thereby causing the tubes to be clean and free from obstructions which might prevent the fusees from being properly positioned within the tubes. The stops 13 are positioned within the tubes 7 at such 30 a point as to cause the upper end 14 of the fusees 12 to extend beyond the upper end of the tubes 7 so that they may be readily grasped by the flagmen so they may be quickly removed from their respective tubes 35 to be used for signal purposes.

When it is desired to attach torpedoes 15 to the fusee holder frame, they may be attached to the intermediate ring 10 by wrapping the ductile ends 16 thereof around the 40 ring 10. The ring 10 may or may not be used in the fusee holder construction, as desired.

When the fusee holder frame is applied to a lantern, the lower or base ring 6 thereof 45 is forced over the lantern until it comes to a position surrounding the lantern base ring 1 and the looped end 2 of the lantern frame wires 3. The ring 6 is forced over the looped ends 2 of the lantern frame, or cage 50 wires 3 so as to create frictional contact therebetween which aids in preventing longitudinal displacement of the fusee holder upon the lantern frame. The ears 4 lie positioned in the offset portions of the tube connecting strips and prevent any rotary or 55 turning displacement of the fusee holder upon the lantern frame, as is manifest.

From the foregoing description, it is evident that I provide a fusee holder for lanterns which can be quickly applied to and 60 over the lantern frame or cage and capable of carrying four fusees for signal purposes, two upon each side of the lantern, in such spaced relation as not to interfere with the 65 rays of light for lantern signalling.

When it is desired to use the lantern without the fusee holder attached thereto, the same can be readily detached therefrom by merely pulling it up over other lantern frame or cage.

The many advantages of the herein described invention will readily suggest themselves to those skilled in the art to which it appertains.

I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall within the scope of the appended claims when fairly construed.

What I claim is:

1. In combination with a lantern having a wire frame including a base ring and terminal ends of lantern frame wires looped thereabout, of a fusee holder detachably applied to the lantern frame and consisting of a wide flat base ring for frictional engagement with the looped end of the lantern frame wires, an upper ring adapted to rest upon the bail ears of the lantern frame, a pair of opposed open ended fusee holder tubes fixed to opposite sides of said base and upper holder rings, means directed inwardly from the walls of the fusee tubes to act as interior stops to prevent the fusees from falling through the tubes, opposed straps connecting opposite pairs of fusee holders near the upper ring of the holder, an off-set in each connecting strap to receive the bail ears of the lantern to prevent turning displacement of the fusee holder upon the lantern frame.

2. In combination with a lantern having a wire frame including a base ring and terminal ends of lantern frame wires looped thereabout, of a fusee holder detachably applied to the lantern frame and consisting of a wide flat base ring for frictional engagement with the looped end of the lantern frame wires, an upper ring adapted to rest upon the bail ears of the lantern frame, a pair of opposed open ended fusee holder tubes fixed to opposite sides of said base and upper holder rings, means directed inwardly from the walls of the fusee tubes to act as interior stops to prevent the fusees from falling through the tubes, opposed straps connecting opposite pairs of fusee holders near the upper ring of the holder, an off-set in each connecting strap to receive the bail ears of the lantern to prevent turning displacement of the fusee holder upon the lantern frame and an intermediate wire ring

connected to the fusee holder tubes a suitable distance above the holder base ring to which torpedoes are attached.

3. In combination with a lantern having a wire frame including a base ring and terminal ends of lantern frame wires looped thereabout, of a fusee holder detachably applied to the lantern frame and consisting of a wide flat base ring for frictional engagement with the looped end of the lantern frame wires, an upper ring adapted to rest upon the bail ears of the lantern frame, a pair of opposed open ended fusee holder tubes fixed to opposite sides of said base and upper holder rings, means directed inwardly from the walls of the fusee tubes to act as interior stops to prevent the fuses from falling through the tubes, opposed straps connecting opposite pairs of fusee

holders near the upper ring of the holder, an off-set in each connecting strap to receive the bail ears of the lantern to prevent turning displacement of the fusee holder upon the lantern frame and an intermediate wire ring connected to the fusee holder tubes a suitable distance above the holder base ring to which torpedoes are attached, opposed off-set portions in the holder base ring and opposed off-set portions in the torpedo carrying ring to permit said rings to pass over the bail ears and bail of the lantern.

4. In combination with a lantern having a wire frame including a base ring and terminal ends of lantern frame wires looped thereabout, of a fusee holder detachably applied to the lantern frame and consisting of a wide flat base ring for frictional engagement with the looped end of the lantern frame wires, an upper ring adapted to rest upon the bail ears of the lantern frame, a pair of opposed open ended fusee holder tubes fixed to opposite sides of said base and upper holder rings, means directed inwardly from the walls of the fusee tubes to act as interior stops to prevent the fuses from falling through the tubes, opposed straps connecting opposite pairs of fusee

holders near the upper ring of the holder, 45 an off-set in each connecting strap to receive the bail ears of the lantern to prevent turning displacement of the fusee holder upon the lantern frame and an intermediate wire ring connected to the fusee holder tubes a suitable distance above the holder 50 base ring to which torpedoes are attached, opposed off-set portions in the holder base ring and opposed off-set portions in the torpedo carrying ring to permit said rings to 55 pass over the bail ears and bail of the lantern.

5. In combination with a lantern having a wire frame including a base ring and terminal ends of lantern frame wires looped thereabout, of a fusee holder detachably applied to the lantern frame and consisting of a base ring, an upper ring, a pair of fusee holder tubes fixed to said rings in opposed relation, connecting members for said tubes near their upper ends and below the upper 60 ring, means to prevent the fuses from falling through the fusee holder tubes, off-set portions in the fusee holder tube connecting members to receive the lantern bail ears 65 and prevent turning displacement of the 70 fusee holder upon the lantern frame.

6. In combination with a railroad lantern, of a fusee carrier detachably carried by the lantern cage, said carrier comprising a base ring, an upper ring, a pair of suitably spaced fusee container tubes having open ends fixed to opposite sides of said rings, means to prevent turning displacement of the fusee carrier upon the lantern cage and means to prevent downward movement of the fusee carrier upon the lantern cage beyond a predetermined distance.

In testimony whereof, I have hereunto signed my name to the specification.

ANNA C. NORDMAN.
